UNITED STATES PATENT OFFICE.

HENRY T. RATCLIFFE, OF HUTCHINSON, KANSAS.

ROTARY VALVE.

1,196,149.

Specification of Letters Patent. Patented Aug. 29, 1916.

Application filed January 10, 1916. Serial No. 71,314.

To all whom it may concern:

Be it known that I, HENRY T. RATCLIFFE, a citizen of the United States, residing at Hutchinson, in the county of Reno and State of Kansas, have invented certain new and useful Improvements in Rotary Valves, of which the following is a specification, reference being had to the accompanying drawings.

10 This invention relates to valves, and particularly to turbinate valves, that is, valves which have a rotary motion akin to the motion of a top.

15 The general object of the invention is to provide a very simple and effective form of valve which is peculiarly applicable for use with internal combustion engines to control the opening and closing of the inlet and exhaust to the cylinders of these engines.

20 A further object of the invention is the provision of a valve of this character so constructed and arranged that it will permit the inlet port of the engine to be opened its entire extent during the entire inlet stroke and which will permit the exhaust port of 25 the engine to be opened its entire extent during the exhaust stroke of the engine.

25 A further object of the invention is to provide a valve which will open and close the exhaust and inlet ports very quickly thereby giving a quicker action to the motor.

30 A further object of my invention is to very greatly reduce the number of parts necessary to control the inlet and exhaust ports and which requires no grinding and practically no repair.

35 A further object of my invention is to provide a valve which will give the exhaust and intake a free and unobstructed passage, 40 allowing the gas to enter freely to the cylinder while the inlet port is open and permitting the exhaust gases to pass out quickly, resulting in greater power with the same diameter of cylinder and length of 45 stroke and a considerable fuel economy.

45 A further object is to provide one valve which will control both the exhaust and the inlet ports of a cylinder.

50 Other objects will appear in the course of the following description.

55 My invention is illustrated in the accompanying drawings, wherein:

Figure 1 is a fragmentary diametrical section of the cylinder of an internal combustion engine with my invention applied there-

to; Fig. 2 is an inner face view of the section 11 of the valve casing showing a portion of the valve; Fig. 3 is a section on the line 3—3 of Fig. 2; Figs. 4 to 9 are diagrammatic face views of the valve showing its position with relation to the exhaust and inlet ports of the engine at different periods.

60 My improved valve is intended to be applied in conjunction with each cylinder of an internal combustion engine. In Fig. 1 I have illustrated a fragmentary view of one cylinder of an internal combustion engine, designated A, this cylinder having the usual piston connected to the crank shaft (not shown). My improved valve consists of 65 two parts or sections 10 and 11. The part 10 I have illustrated as formed integral with the cylinder A, but this is purely illustrative as the part 10 might be separate and distinct from the cylinder. The two sections 10 and 11 are formed to confront each other and each section is recessed on its inner face so as to form a valve chamber 12 which is relatively shallow. The sections 10 and 11 may be held in engagement with 70 each other in any suitable manner, as by means of screws 13; and the confronting edges or margins of the two sections may be packed as by means of a packing 14. Preferably these sections 10 and 11 are circular 75 in form and the section 11 is formed with a central aperture 15 provided with a suitable bearing 16 which is preferably a ball bearing. The section 10 and the section 11 are each formed with inlet ports 17 and exhaust ports 18. The inlet port 17 on the section 11 is adapted to be operatively connected to any suitable manifold leading from the carburetor while the exhaust port 18 of the section 11 is adapted to be connected to an exhaust pipe and muffler.

80 Disposed in the valve chamber 12 is a circular rotatable valve disk 21, which, adjacent its margin and for a portion of its circumference, is provided with an elongated 85 port 22. The ends of the port 22 are re-entrant so as to form semi-circular portions 23 which project beyond the side edges of the port. The length of the port 22 is 90 preferably equal to the distance between the ports 17 and 18. These ports 17 and 18 have an angular distance between them of about 90 degrees and the length of the port 22 corresponds to this. When the disk 21 95 is in the position shown in Fig. 4 it will be 100 in the position shown in Fig. 4 it will be 105 110

exactly between the exhaust port and the inlet port, and both of these ports will be closed.

The disk 21 is mounted upon a shaft 24 which extends out through the aperture 15 and is supported by means of ball bearings or other suitable journal bearings 16 and the extremity of the shaft 24 is operatively connected to the engine in such manner that the shaft will be revolved in time with the movement of the corresponding piston. I have illustrated the shaft 24 as being provided at its extremity with the sprocket wheel 25 in turn engaged by a sprocket chain 26 and driven from any suitable rotative part, as for instance, the crank shaft. This is purely illustrative as any means may be used for driving the several shafts 24 of the several valves, and this means will vary with the views of different manufacturers and with the construction of different motors.

In order to reduce as much as possible the friction between the valve disk 21 and the casing formed by the sections 10 and 11 and at the same time prevent leakage of gas around the ports 18 and of the exhaust around the port 17, I preferably form the inner faces of the sections 10 and 11 with the grooves 28 within which packing rings 29 are disposed. These packing rings project above the inner faces of the sections 10 and 11 about .002 of an inch so that the valve disk will not touch either of the sections 10 or 11 but will only touch the packing rings. Thus the only friction will be that of the disk against the faces of the packing rings. A thin film of oil will be used to fill the spaces between the inner faces of the members 10 and 11 and the disk 21 so as to make the joint perfectly tight and cause the valve disk to run easily without friction, but it is preferable to use no oil within the interior of the chamber 12 and only apply oil when needed to the bearings for the shaft 24. The valve may be lubricated through the packing rings and the sections 10 and 11 may be formed by castings having water jackets so as to keep the valve cool.

The operation of my invention is illustrated in Figs. 4 to 9. In Fig. 4 the valve is shown at the moment when the exhaust port has closed and just before the inlet port is opened. This is at the beginning of the suction stroke. When the piston has completed one-half of its suction stroke the valve has rotated to the position shown in Fig. 5 and when the suction stroke is completed the piston starts on its compression stroke and the valve is rotated to such a position that the port 22 has entirely passed the inlet port 17. While the valve is in the position shown in Fig. 7 the compression stroke is completed and the charge ignited,

and at the completion of the working stroke the valve has shifted to the position shown in Fig. 8 where the exhaust port is just about to be opened. When the exhaust stroke is one-half completed the valve has shifted to the position shown in Fig. 9.

It will be seen that this valve is composed of only one moving part and that with this valve a rotor will be very much simplified as the use of the valve will do away with the two valves now in use to control the inlet and the exhaust, the valve springs therefor, washers, cotter pins, bushings, and valve rods. In fact it will do away with twelve parts for each cylinder of the engine, thus doing away with forty-eight parts on a four-cylinder motor, seventy-two parts on a six-cylinder motor, and ninety-six parts on an eight-cylinder motor. Furthermore, it is obvious that this valve will do away with the cam shaft ordinarily used for operating the intake and exhaust valves. One of the advantages of this valve is that it requires no grinding as it does not hammer against metal constantly, and a further advantage resides in the fact that on account of its opening and closing very quickly the motor will operate with more "snap." With the valve now in use the piston in each cylinder has to move one-half of the piston stroke before the suction valve is wide open. In other words, if the piston has a six inch stroke with the valve now in use the piston will travel three inches before the suction valve is fully opened, while with my valve the valve is wide open when the piston starts on its suction stroke. With my valve the valve very quickly opens to its fullest extent very shortly after the piston has started on its suction stroke. The piston has only to move about one-eighth of an inch before the valve is fully open and the valve remains fully open for nearly the full length of the stroke. This relieves the cylinder of atmospheric pressure at the end of the stroke. This valve gives a free and unobstructed passage to the gas and the exhaust vapors and the result is more power with the same diameter of cylinder and the same stroke and a greater economy of fuel.

Having described the invention, what I claim is:

A valve of the character described including oppositely disposed casing sections, each section being recessed upon its inner face to thereby provide a relatively shallow valve chamber, the sections being provided with registering inlet and exhaust ports and the inner faces of said sections having annular grooves surrounding the inlet ports and the exhaust ports, packing rings disposed in said grooves and confronting each other, a shaft entering one face of the casing, a valve disk mounted on the shaft and

having a relatively elongated port adapted to successively register with the inlet and the exhaust ports, said valve disk being spaced from the inner faces of the casing sections but having gas-tight engagement with the opposed faces of the packing rings.

In testimony whereof I hereunto affix my signature in the presence of two witnesses.

HENRY T. RATCLIFFE.
